UNITED STATES PATENT OFFICE.

JAMES H. HOOKER, OF EDENFIELD, FLORIDA.

BOX.

No. 797,203.

Specification of Letters Patent.

Patented Aug. 15, 1905.

Application filed September 27, 1904. Serial No. 226,335.

To all whom it may concern:

Be it known that I, JAMES H. HOOKER, a citizen of the United States, residing at Edenfield, in the county of Sumter, State of Florida, have invented certain new and useful Improvements in Boxes; and I do hereby declare the following to be a full, clear, and exact description of the invention, such as will enable others skilled in the art to which it appertains to make and use the same.

This invention relates to boxes or crates, and more particularly to the class of folding or knockdown boxes or crates, the object of the invention being to provide a cheap and simple construction which when set up will be rigid and durable, which when knocked down will occupy a small space, and in which the operation of setting up and knocking down will consume little time.

In the drawings forming a portion of this specification, and in which like numerals of reference indicate similar parts in the several views, Figure 1 is a side elevation of the box embodying the present invention. Fig. 2 is a top plan view with the top of the box removed. Fig. 3 is an end elevation. Fig. 4 is a vertical section taken longitudinally through the box.

Referring now to the drawings, there is shown a box comprising sides 5 and 6, ends 8 and 9, a bottom 10, and a top 11. The ends have formed therein adjacent to their upper edges, respectively, transverse lines of perforations 12, through which are engaged the three longitudinal tie rods or bolts 13, the ends of which project through the ends of the box and are provided with eyes 14, which aline transversely of the box, the eyes at each end having a key 15 engaged therein. Adjacent to the bottom edges of the ends 8 and 9 are also transverse lines of perforations 17, in which are engaged longitudinal tie rods or bolts 20, having eyes 21 at their ends through which are engaged keys 22 and 23. Intermediate of these upper and lower series or lines of perforations in each end of the box is a transverse line or series of perforations 24, in which are engaged the longitudinal tie rods or bolts 25, having eyes 26 at their ends in which are engaged the keys 27. Between the ends of the box are disposed the sides 5 and 6, which are held against inward displacement by the cleats 28 and 29 on the inner faces of the ends, while outward displacement is prevented by an upper, a lower, and an intermediate se-

ries of three tie rods or bolts 30, 31, and 32, respectively, which are engaged through perforations 34, 35, and 36, respectively, in the sides of the box, the tie rods or bolts of each series being connected at their ends by a key 39, 40, and 41, respectively, which are engaged in the alining eyes 42, 43, and 44, respectively, of the rods or bolts. In this way the sides and ends of the box are held securely together, it being noted that the corresponding series of longitudinal and transverse tie rods or bolts are in a common plane, such rods or bolts being arched in opposite directions at their points of crossing. The intermediate series of tie rods or bolts serves as a support for a pasteboard or other partition upon which may be placed the ordinary cell-cases for eggs or fruit.

When the box is to be knocked down, it is only necessary to withdraw the keys from the ends of the tie rods or bolts, when the parts may be readily removed, it being noted that the bottom 10 of the box is held between cleats 46 on the sides and ends of the box, while the top may be hinged to a side in the usual manner.

What is claimed is—

1. A knockdown box comprising sides and ends having each upper, lower and intermediate series of transverse perforations, tie-rods extending longitudinally within the box and engaging the perforations of the ends and extending outwardly therethrough and having eyes in their extremities, keys engaged in the eyes, transverse tie-rods engaged in the perforations of the sides and extending therethrough and having eyes at their extremities with which are engaged keys, the corresponding longitudinal and transverse bars being arched in opposite directions at their points of intersection and lying with their remaining portions in common planes respectively, a bottom held between the ends and sides, and a top.

2. A knockdown box comprising a bottom, top, sides and ends, the sides and ends having each upper, lower and intermediate series of transverse perforations, cleats secured to the ends of the box to prevent inward displacement of the sides, cleats secured to the sides to prevent displacement of the bottom of the box, tie-rods extending longitudinally within the box and engaging the perforations of the ends and having eyes at their extremities, keys engaged in the eyes, transverse tie-rods

engaged in the perforations of the sides and extending therethrough and having eyes at their extremities with which are engaged keys, the keys at the sides and ends of the box being independent one set of another, the corresponding longitudinal and transverse bars being arched in opposite directions at their points of intersection and lying with their re-

maining portions in common planes respectively.

In testimony whereof I affix my signature in presence of two witnesses.

JAMES H. HOOKER.
